CRACKING OF HYDROCARBON OILS

Lyman C. Huff, Chicago, Ill., assignor, by mesne assignments, to Universal Oil Products Company, Chicago, Ill., a corporation of Delaware

Application February 26, 1930, Serial No. 431,405
Renewed April 30, 1935

5 Claims. (Cl. 196—49)

This invention relates to the art of treating hydrocarbon oils by the method of thermal decomposition known as cracking and has for its object the production of hydrocarbons, within the boiling range of motor fuel, which are of a highly unsaturated nature and are especially desirable for use as fuel in internal combustion engines employing high compression pressures.

With the continually increasing use of high compression internal combustion engines employing a carbureted fuel the demand for suitable fuel which will withstand the high compression pressures employed without appreciable detonation has steadily mounted until such suitable fuel has come to demand considerable premium in the market.

In a cracking process of the liquid-vapor-phase type which is in wide commercial use, one of the usual methods of operation is to produce a distillate containing from 60 to 85% more or less, of material falling within the boiling range of gasoline and which is redistilled to effect a separation of this gasoline-like component. The residual material commonly termed pressure distillate bottoms, which is left from this redistillation of the pressure distillate is exceptionally suitable for the production of a highly anti-knock motor fuel when processed under high temperature or so called vapor-phase cracking conditions. Inasmuch as these so-called pressure distillate bottoms are a highly refractory cracking stock and would considerably lower the throughput if returned and reprocessed in the liquid vapor-phase system, it would be economical to treat them separately in a system employing conditions most suitable for the conversion of this particular oil.

My process comprises a liquid-vapor-phase system wherein the pressure distillate vapors are further fractionated in a secondary fractionating tower within the system and wherein the reflux, corresponding to pressure distillate bottoms, from this secondary fractionating tower is reconverted under vapor phase cracking conditions.

A salient feature of my invention is the optional use of a residuum revaporizing or flash distilling system wherein the residual products from both the liquid-vapor-phase and the vapor-phase systems may be released under reduced pressure and their combined redistillation thereby effected.

My process also provides for the use of reflux from the dephlegmator of the flash system, consisting of reflux condensate combined with pre-heated and topped raw oil charging stock, as a cooling medium in the vapor-phase dephlegmator

or in the liquid-phase dephlegmator, or in both.

The process also provides for the return of reflux from the dephlegmator of the vapor-phase system to the liquid-phase heating element and its reconversion therein.

The attached drawings, Fig. 1 and Fig. 2 represent a diagrammatic elevation, not drawn to scale showing one particular construction of an apparatus to which my process is adapted. The raw oil enters the process through line 1 and is fed by means of pump 2 through line 3 and valve 4 into dephlegmator 58 of the flash system. Here the oil is stripped of its natural gasoline content, if any, by heat from the vapors arising in the dephlegmator. The preheated and stripped raw oil together with reflux condensate from the vapors may collect in the bottom of the dephlegmator 58 and pass therefrom through line 5 and valve 5' to the hot feed pump 6. From here the oil may be fed through valve 7, line 8 and valve 8' into fractionating tower 42 of the vapor-phase system, or through valve 9 and line 10 into the primary dephlegmator 21 of the liquid-vapor-phase system or by proper manipulation of the valves 7 and 9 any portion may be fed in either direction.

The oil thus fed into the vapor-phase fractionating tower 42 assists in cooling and fractionating the vapors arising therein. Its unvaporized portions are collected together with the reflux condensate in the bottom of the tower and pass through line 11, valve 11', heat exchanger or reboiler 12, through line 12' and valve 13' to pump 13 and is then fed by pump 13 through line 68 and valves 69 and 70 into line 16'. The heat exchanger or reboiler 12 serves to strip the reflux liquid from fractionating tower 42 of the low boiling gasoline-like constituents which may be contained therein by reboiling the reflux liquid by indirect contact with hot vapors from the vapor-phase reaction chamber 39 at the same time partially cooling the cracked vapors. The low boiling constituents or light ends thus separated may pass through line 14 and valve 14' back into the fractionating tower 42 at a point above the reflux level.

Oil fed into the primary dephlegmator 21 through line 10 serves the same purpose of assisting cooling and fractionation in this portion of the apparatus, collects with other reflux condensate in the bottom of this fractionating tower 21 and passes through line 15 and valve 15' to pump 16. Oil from pump 16 combines in line 16' with the oil fed from pump 13 through line 68 and the total combined feed from line 16' is

pumped through the liquid-vapor-phase heating element 17.

This liquid-vapor-phase heating element is located in any suitable furnace 18. The oil passing through the heating element 17 is heated to the desired temperature under any desired pressure and passes through line 19 and valve 19' into the liquid-vapor-phase reaction chamber 20. Vapors from this reaction chamber pass through line 68 and valve 68' into the primary dephlegmator 21 where they are cooled and fractionated by incoming oil from line 10 as above described.

Dephlegmator 21 may be any suitable fractionating device employing any suitable fractionating means such as perforated pans or packing.

The vapors leaving primary dephlegmator 21 will consist of a small amount of fixed gas and the product commonly known as pressure distillate which ordinarily requires redistillation for the separation of its gasoline-like constituents. In this process these vapors pass through line 22 and valve 22' into secondary dephlegmator or fractionating tower 23. By means of further fractionation in this secondary tower the lighter portions of the pressure distillate which correspond to gasoline are separated from the heavier portions. These lighter portions may pass as vapor through line 24, valves 24' and 25 into the upper portion of the vapor-phase fractionating tower 42 or they may pass through line 26 controlled by valve 27 through condenser 28, line 28' and valve 29' into receiver 29 wherein the liquid products are separated from the fixed gas—the fixed gas being released through line 30 controlled by valve 31 and the liquid products being withdrawn to storage or elsewhere through line 32 controlled by valve 33.

Reflux, corresponding to what is commonly known as pressure distillate bottoms, from the secondary fractionating tower 23 may pass through line 34, valve 34' and by means of pump 35 may be fed through valve 35' and line 36' to the vapor-phase heating element 35 which is located in any suitable furnace 31. This material after being subjected to the desired conditions of temperature and pressure in heating element 36 may pass in a substantially vaporized state through line 38 and valve 38' and into the vapor-phase reaction chamber 39. Vapors from this reaction chamber may pass through line 40 and valve 41 to the heat exchanger or reboiler 12 where they reboil the bottoms from the fractionating tower 42 and are thereby partially cooled as above described, and thence continue through line 40 and valve 41' into the vapor-phase fractionating tower 42.

Tower 42 may take the form of any suitable fractionating device and is preferably a tower of the packed or bubble type. Vapors leaving this tower pass through line 43, valve 43', condenser 44, line 44' and valve 45' into receiver 45 where the condensed liquid produced is separated from the uncondensed gas. The fixed gas is released through line 46 controlled by valve 47 and the liquid product is withdrawn to storage or elsewhere through line 48 controlled by valve 49.

The liquid residual product from reaction chamber 20 of the liquid-vapor-phase system may be withdrawn by well known means not shown for use as fuel in the system, or to storage or elsewhere. The liquid residual product from the reaction chamber 39 of the vapor-phase system may likewise be separately withdrawn by means not shown or it may be withdrawn through line 50 and valve 51 into line 52 where it may com-

bine, if desired, with the residual liquid withdrawn from reaction chamber 20 through line 53 and valve 54. Either one of these residual products or the two combined in any proportion may pass through line 52 and valve 55, where the pressure is substantially reduced, into flash distilling chamber 56. The lighter portions of the residual liquids are here reevaporized by their own latent heat and may pass through line 57 and valve 57' into flash dephlegmator 58.

Flash dephlegmator 58 may be any suitable fractionating device, but is preferably a tower containing perforated pans or similar fractionating means. The flashed vapors are herein fractionated and partially cooled by incoming raw oil and the lighter portions of the vapors may pass through line 59, valve 59', condenser 60, line 60' and valve 61' into receiver 61 where the condensed liquid is separated from the uncondensed gas, the gas being released through line 62 controlled by valve 63 and condensate being withdrawn through line 64 controlled by valve 65.

The condensed liquid products from any of the receivers 29, 45 or 61 may be returned in any desired quantity by well known means not shown, to their respective fractionating towers 23, 42 and 58 to assist cooling and fractionation in the fractionating towers. The flashed residual product from flash chamber 56 may be withdrawn through line 66 and valve 67 to storage or elsewhere.

Any pressure ranging from sub-atmospheric to high superatmospheric pressures, say up to 2000 pounds per square inch more or less, may be employed throughout the system or differential pressures may be employed between various portions of the apparatus. Cracking temperatures ranging from 700 to 1400 degrees F. more or less, may be employed in either or both heating elements but preferably temperatures employed in heating element 17 are within the range of what is commonly termed liquid-phase cracking temperatures, say 700 to 1000 degrees F., or thereabouts, and temperatures employed in the heating element 36 are preferably maintained within the range of what are commonly termed vapor-phase cracking temperatures, e. g. 900 to 1400 degrees F. more or less.

As a specific example of one of the many operations possible with my process and in the apparatus just described a 32 degree A. P. I. gravity Mid-Continent gas oil is used as charging stock for the liquid-vapor-phase process. The total charge is fed to the fractionating zone of the flash system and in combination with the reflux condensate from this flash dephlegmator is fed in part to the primary dephlegmator of the liquid-vapor-phase system and in part to the fractionating tower of the vapor-phase system. Reflux condensate and preheated raw oil from both of these fractionating zones is subjected in the liquid-vapor-phase heating element to an outlet temperature of approximately 900 degrees F. under a pressure of approximately 225 pounds per square inch.

Very little liquid is maintained in the reaction chamber of the liquid-vapor-phase system and consequently little or no coke is deposited in this chamber. Substantially the same pressure is maintained in the chamber 20 and tower 21 as that maintained in the heating element 17 but this pressure is reduced in the secondary fractionating tower of the liquid-vapor-phase system to approximately 90 pounds per square inch.

Reflux condensate corresponding to pressure distillate bottoms from the secondary liquid-vapor-phase fractionating tower comprises the charging stock to the vapor-phase system. This 5 oil is heated in the vapor-phase heating element to a temperature of approximately 1200 degrees F., and a substantially equalized pressure of approximately 80 pounds per square inch is maintained throughout the vapor-phase system.

10 Residual oil from both the liquid-vapor-phase and the vapor-phase reaction chambers is flash distilled at a reduced pressure at approximately 20 pounds per square inch.

15 Recovery of the various products from an operation such as outlined may be somewhat as follows:

20 Approximately 54% of distillate boiling within the range of motor fuel and equivalent in anti-knock rating to a blend of approximately 35% benzol with 65% straight run gasoline may be recovered from the liquid-vapor-phase system.

25 The system in this particular case is so operated that a relatively high percentage of pressure distillate bottoms are produced and from this oil approximately 22% of gasoline based on the 30 charging stock may be recovered by processing in the vapor-phase system. This vapor-phase gasoline while quite possibly of lower gravity than ordinary cracked or straight run gasoline may 35 still fulfill the boiling range requirements for regular or even premium motor fuel and may show a benzol equivalent of some 60% or thereabouts.

40 About 10% of a relatively heavy distillate is recovered from the flash system and a final heavy residual product from the process removed from the flash chamber may represent only 8%, more or less, of the original charging stock. The remaining 6% or thereabouts may represent the coke, gas produced and loss in processing.

I claim as my invention:

1. A hydrocarbon oil cracking process which 45 comprises initially cracking the oil in a primary cracking zone under sufficient pressure to retain a substantial portion thereof in the liquid phase, separating the thus treated oil into vapors and unvaporized oil, simultaneously cracking a condensate separated from said vapors in the vapor phase in a second cracking zone, flash distilling said unvaporized oil by pressure reduction and dephlegmating the resultant flashed vapors independently of the vapor phase cracked vapors from said second cracking zone and in contact with fresh charging oil for the process thereby forming a mixture of unvaporized charging oil and flash reflux, dephlegmating the vapors from said primary cracking zone and the vapors from said second cracking zone in contact with portions of said mixture, then supplying the charging oil and resultant reflux condensate to the primary cracking zone, and condensing the dephlegmated vapors.

2. A process as defined in claim 1 further characterized in that said condensate comprises a secondary reflux condensate produced by secondary dephlegmation of the vapors from said primary cracking zone.

3. A hydrocarbon oil cracking process which

comprises initially cracking the oil in a primary cracking zone under sufficient pressure to retain a substantial portion thereof in the liquid phase, separating the thus treated oil into vapors and unvaporized oil, simultaneously cracking a condensate separated from said vapors in the vapor phase in a second cracking zone, flash distilling said unvaporized oil by pressure reduction and dephlegmating the resultant flashed vapors in contact with fresh charging oil for the process thereby forming a mixture of unvaporized charging oil and flash reflux, passing the vapors from said primary and second cracking zones to independent dephlegmating zones, dividing said mixture and introducing a portion thereof into each 15 of said independent dephlegmating zones to serve as a dephlegmating medium therein, supplying unvaporized charging oil and reflux condensate from said dephlegmating zones to the primary cracking zone, and condensing the vapors un- 20 condensed in said dephlegmation.

4. A hydrocarbon oil conversion process which 25 comprises cracking hydrocarbon oil in a primary cracking zone under sufficient pressure to retain a substantial portion thereof in liquid phase, separately removing vapors and unvaporized oil from said zone, fractionating the vapors to form a relatively heavy reflux condensate and a lighter reflux condensate, returning such heavy reflux condensate to said zone, cracking the lighter reflux condensate substantially in vapor phase in 30 a second cracking zone maintained at higher temperature than said primary zone, fractionating the resultant vapor phase cracked vapors, reducing the pressure on the unvaporized oil 35 withdrawn from said primary zone and thereby flash distilling the same, fractionating resultant flashed vapors independently of said vapor phase cracked vapors thereby forming flash reflux condensate, introducing such flash condensate into 40 contact with the vapor phase cracked vapors undergoing fractionation and supplying resultant liquid products to the primary cracking zone, and finally condensing the fractionated vapors.

5. A conversion process which comprises 45 cracking hydrocarbon oil in a primary cracking zone under sufficient pressure to retain a substantial portion thereof in liquid phase, simultaneously cracking a lighter oil substantially in vapor phase in a second cracking zone maintained at higher temperature than said primary zone, fractionating resultant vapor phase cracked vapors to condense heavier fractions thereof, removing unvaporized oil from said primary zone and flash distilling the same by pressure reduction, fractionating resultant flashed vapors independently of said vapor phase cracked vapors, introducing flash reflux thus formed into contact with said vapor phase cracked vapors undergoing fractionation and supplying liquid products 60 of this fractionating step to said primary zone, removing vapors from the primary zone and fractionating the same independently of said vapor phase cracked vapors, supplying resultant reflux condensate to the second cracking zone as 65 said lighter oil, and finally condensing the fractionated vapors.
